Sawyer, Atty.

UNITED STATES PATENT OFFICE.

BANCROFT G. BRAINE, OF NEW YORK, N. Y.

RAILWAY-RAIL JOINT.

SPECIFICATION forming part of Letters Patent No. 659,387, dated October 9, 1900.

Application filed November 1, 1898. Renewed March 10, 1900. Serial No. 8,227. (No model.)

To all whom it may concern:

Be it known that I, BANCROFT G. BRAINE, a citizen of the United States, residing at New York, county of Kings, and State of New York, have invented certain new and useful Improvements in Railway-Rail Joints, fully described and represented in the following specification and the accompanying drawings, forming a part of the same.

10 The object of this invention is generally to provide an improved joint for the abutting ends of railway-rails, and especially to improve the construction of joints of that class in which the joint-plates are formed with bearing portions or faces to bear against and wedge between the under side of the head of the rail and the upper side of the base-flange of the rail and have doubled base portions extending beyond and then inwardly beneath the 15 base-flange of the rail, so as to bear against the bottom of the rail-flange as well as against the upper side thereof. I have aimed to improve the construction of joints of this class by providing a joint-plate of greater strength, 20 durability, and stiffness for the weight of metal employed than has heretofore been produced.

As a full understanding of the invention can best be given by a detailed description in 25 connection with drawings showing constructions embodying the various features thereof in the preferred form, such a description will now be given in connection with the accompanying drawings, and the features forming 30 the invention will afterward be specifically pointed out in the claims.

In said drawings, Figure 1 is a perspective view showing one side of the rail-joint shown in section in Fig. 2. Fig. 2 is a section on line 35 2 of Fig. 1. Fig. 3 is a similar section of a joint formed with a joint-plate on one side of the rail of a modified construction and showing by dotted lines such modified construction on the other side of the rail also. Fig. 4 40 is a similar sectional view showing on one side of the rail a joint-plate to be used when auxiliary guard-rails similar to that shown in Fig. 5 are employed. Fig. 5 is a sectional view of a built-up rail formed of a rail proper 45 and an auxiliary guard-rail secured thereto. Fig. 6 is a side view showing parts of abutting ends of rails provided with guard-rails such

as shown in Fig. 5 and joined by means of the joint shown in Fig. 4. Fig. 7 is a sectional view of a built-up rail formed of a rail proper and an auxiliary vehicle flange-rail secured thereto.

Referring to the drawings, and first to Figs. 1 and 2, A represents a common form of T-rail, of which a is the head, a' the base-flange, and a^2 the web.

B are the joint-plates by which the abutting ends of the rail-sections are secured together. Each of the plates B is formed with a vertical web portion b , bearing-face b' to engage the inclined under face of the head of the rail, bearing-face b^2 to engage the inclined upper face of the flange a' of the rail, and with a doubled base portion b^3 , which extends beyond and then inwardly beneath the rail-flange a' to form a bearing-face b^4 to engage the under side of the rail-flange. The joint-plates are proportioned according to the size and form of the rails to be joined, so that the various bearing-faces of the joint-plates will bear against the corresponding parts of the rails when the joint-plates are forced toward each other on opposite sides of the rail, preferably, as shown, by bolts 10 passing through the web of the rail and the webs b of the joint-plates. The plates are also formed to allow wear on the bearing-faces to be taken up by forcing the plates farther together or toward the rail-web. As thus far described the joint-plates are similar to joint-plates which have 85 been heretofore used in joints of the class before referred to.

In such joint-plates as heretofore made a proportionately-large part of the metal is in the doubled base portions of the joint-plate, 90 and the web portions of the plate, in which the bolt-holes are formed, are consequently subjected to great strains in supporting the rail ends during the passage of trains. I have aimed in my improvement to obtain a more 95 efficient distribution of metal, producing a plate better adapted to withstand the strains to which it is subjected; both without fracture and with a minimum deflection, and in which the web portion of the plate will not 100 be subjected to so great strains as heretofore, and, further, to obtain such a distribution of the metal as to avoid warping in cooling and that the development of internal strains in

cooling will be largely if not wholly avoided, thereby adding to the strength and stiffness of the joint, and to secure these results without introducing any objectionable features 5 into the plate. For this purpose I form the joint-plates with a top flange b^5 , extending outward horizontally from the upper portion of the web portion b , and in order not to interfere with the wheel-flanges the top 10 flange b^5 is preferably formed with its upper face below the upper extremity of the vertical portion of the plate to provide sufficient clearance-space between the top of the rail and said flange for the wheel-flange and to 15 allow for wear of the rail and tread of the wheel.

It is only necessary to have the top flange b^5 of the joint-plate for the inside of the rail formed with its upper face below the upper 20 extremity of the vertical portion b of the joint-plate to provide clearance-space for the wheel-flange; but I prefer to use the same form of joint-plate on both sides of the rail, as shown in Fig. 2, as I secure a sufficiently-25 good result from the flange b^5 in this position and avoid the increased cost of using two forms of joint-plates. I may, however, use on the outside of the rail a joint-plate in which the upper face of the flange b^5 is not 30 below the upper extremity of the vertical portion of the plate, as shown on the right-hand side of the rail in Fig. 3, in which the flange b^5 is positioned so that its upper face extends horizontally outward from the 35 upper extremity of the vertical portion of the plate b . It should be observed, however, in this case that the upper face of the flange b^5 should not extend above the upper bearing-face b' of the joint-plate for a distance out- 40 ward therefrom at least sufficient so that there can be no interference with the inward movement of the plate in taking up wear on the bearing-faces of the plate and the rail. In some cases where the head of the rail is of 45 sufficient depth relatively to the flange of the car-wheels it may be found feasible to employ for both sides of the rail joint-plates of the form shown on the right-hand side of Fig. 3.

50 It will be seen that in addition to the advantages above pointed out I provide a joint-plate of the class above referred to having a doubled base portion of a form which enables the distribution of metal with relation to the 55 neutral axis to be readily varied according to the metal employed and the conditions to be met, as by merely extending or shortening the top flange.

Fig. 5 shows a section of a T-rail provided 60 with a common form of auxiliary guard-rail C , which is secured to the rail proper by bolts passed through the web a^2 of the rail and through a lower vertical portion or web of the guard-rail. When guard-rails of this kind are 65 employed, difficulty has heretofore been experienced in the use of rail joint-plates of the class hereinbefore referred to or of other joint-

plates having portions extending between the head and base-flange of the rail. I avoid this difficulty by using on the inside or guard-rail 70 side of the rail joint-plates having an upwardly-extending guard-flange or guard-rail section adapted to extend between the sections of and take the place of the regular guard-rail of the joint, the regular guard-rails being cut 75 away or made of a length to end at such a distance from the abutting ends of the sections of the rail proper as to leave a space between the ends of the guard-rail sections to receive and be filled by the joint-plate and its section 80 of guard-rail.

Fig. 4 shows in section a joint having a joint-plate of the preferred form for use with a guard-rail in this manner. As here shown, the joint-plate B' for the inside of the rail is 85 formed with a guard-flange or guard-rail portion C' , formed by providing an upward extension to the top flange b^5 , so as to form a flange extending outwardly and then upwardly from the upper portion of the vertical 90 portion b of the joint-plate, the upper face of the horizontal portion of the flange being preferably below the upper extremity of the vertical portion b of the joint-plate sufficiently to give clearance-space for the wheel-flanges. 95 This outwardly and upwardly extending flange is thus adapted to form a portion of the guard-rail between the ends of adjacent sections of the regular guard-rail in addition to performing the office of the flange b^5 . Fig. 100 6 shows in inside side elevation the abutting ends of sections of a rail provided with a guard-flange such as shown in Fig. 5 and with their ends joined by a joint-plate formed with a guard-rail section, as shown in Fig. 4. 105

Fig. 7 shows a common form of built-up street-railway rail formed from a T-rail provided with an auxiliary vehicle flange-rail D , secured to the inside side thereof. With auxiliary vehicle flange-rails of this kind the same 110 difficulty has been experienced in the use of joint-plates as with the auxiliary guard-rails before referred to. I avoid this difficulty by making the top flange of the joint-plate for the inside of the rail of a form to correspond 115 with the flange of the auxiliary rail, so as to form a vehicle-flange adapted to extend between the sections of and take the place of the flange of the auxiliary vehicle flange-rail at the joint, the sections of the auxiliary rail 120 being of a length to end at such a distance from the abutting ends of the sections of the rail proper as to leave a space between the ends of the auxiliary rail-sections to receive and be filled by the joint-plate and its flange. 125

Referring again to Fig. 4, such a joint-plate of the preferred form is formed by providing the joint-plate B' , as indicated in dotted lines, with a top flange formed to correspond with the vehicle-flange of the auxiliary rail, as 130 shown in Fig. 7, in place of the guard-flange shown in full lines.

What I claim is—

1. A railway-rail-joint plate comprising a

vertical web portion to extend between the head and base-flange of the rail, a doubled base portion extending outward and then inwardly to embrace the base-flange of the rail, and an outwardly-extending strengthening top flange of a width from the inner side of the joint-plate substantially equal to the depth of the rail-flange-receiving slot of the doubled base portion and the upper face of

5 which top flange is below the upper extremity of the vertical portion to provide clearance-space for the wheel-flanges, and said joint-plate having bearing-faces to engage the under face of the head of the rail, the upper

10 face of the base-flange of the rail, and the under face of the base-flange of the rail, substantially as described.

2. A railway-rail-joint plate comprising a vertical web portion to extend between the head and the base-flange of the rail, a doubled base portion extending outward and then inwardly to embrace the base-flange of the rail, and an outwardly-extending strengthening top flange of a width from the inner side of the joint-plate substantially equal to the depth of the rail-flange-receiving slot of the doubled base portion and said joint-plate having bearing-faces to engage the under face of the head of the rail, the upper face of the base-flange of the rail, and the under face of the base-flange of the rail, substantially as described.

3. A railway-rail-joint plate comprising a vertical web portion to extend between the head and base-flange of the rail, a doubled base portion extending outward and then inwardly to embrace the base-flange of the rail, and an outwardly-extending strengthening top flange of a width from the inner side of the joint-plate substantially equal to the depth of the rail-flange-receiving slot of the doubled base portion having an upward extension to form a guard-flange C, and said joint-plate having bearing-faces to engage the under face of the head of the rail, the upper face of the base-flange of the rail, and the under face of the base-flange of the rail, substantially as described.

4. In a railway-rail joint, the combination with adjacent rail-sections, of a joint-plate overlapping the abutting ends of the rail-sections comprising a vertical web portion extending between the head and base-flange of the rail, a doubled base portion extending outward beyond and then inwardly beneath the base-flange of the rail, and an outwardly-extending strengthening top flange of a width from the inner side of the joint-plate substantially equal to the depth of the rail-flange-receiving slot of the doubled base portion the upper face of the top flange of the inside plate being below the upper extremity of the vertical portion of the plate to provide clearance-space for the wheel-flanges, substantially as described.

5. A railway-rail joint comprising joint-plates on opposite sides of the rail overlapping the abutting ends of adjacent rail-sections, and means for forcing said plates toward each other, said plates comprising each

extending strengthening top flange of a width from the inner side of the joint-plate substantially equal to the depth of the rail-flange-receiving slot of the doubled base portion, and said joint-plate having bearing-faces engaging the under face of the head of the rail, the upper face of the base-flange of the rail, and the under face of the base-flange of the rail, substantially as described.

6. A railway-rail joint comprising joint-plates on opposite sides of the rail overlapping the abutting ends of adjacent rail-sections, and means for forcing said plates toward each other, said plates comprising each a vertical web portion extending between the head and the base-flange of the rail, a doubled base portion extending outward beyond and then inwardly beneath the base-flange of the rail, and an outwardly-extending strengthening top flange of a width from the inner side of the joint-plate substantially equal to the depth of the rail-flange-receiving slot of the doubled base portion, and having bearing-faces to engage the under face of the head of the rail, the upper face of the base-flange of the rail, and the under face of the base-flange of the rail, substantially as described.

7. A railway-rail joint comprising joint-plates on opposite sides of the rail overlapping the abutting ends of adjacent rail-sections, and means for forcing said plates toward each other, said plates comprising each a vertical web portion extending between the head and the base-flange of the rail, a doubled base portion extending outward beyond and then inwardly beneath the base-flange of the rail, and having bearing-faces to engage the under face of the head of the rail, the upper face of the base-flange of the rail, and the under face of the base-flange of the rail, and having an outwardly-extending strengthening top flange of a width from the inner side of the joint-plate substantially equal to the depth of the rail-flange-receiving slot of the doubled base portion the upper face of the top flange of the inside plate being below the upper extremity of the vertical portion of the plate to provide clearance-space for the wheel-flanges, substantially as described.

In testimony whereof I have hereunto set my hand in the presence of two subscribing witnesses.

BANCROFT G. BRAINE.
